ABSTRACT: A sputter-ion pump in which the cathodes are constructed of at least two different reactive and slow sputtering elements, one or more of the elements being a transition metal such as titanium and the other element being a transition metal of another reactive metal or semiconductor. The relative amounts of the two elements being such that the cathodes contain not less than 10 percent and not more than 90 percent of transition metal by effective surface area.

METHOD AND APPARATUS FOR PRODUCING ALLOYED GETTER FILMS IN SPUTTER-ION PUMPS

STATEMENT OF THE INVENTION

This invention relates to sputter-ion pumps and more particularly to a sputter-ion pump and pumping method in which the getter film is formed by combining two or more different reactive metals, one of which is a transition metal such as titanium.

DESCRIPTION OF THE PRIOR ART

There have been many attempts in the prior art to improve the pumping capability of sputter-ion pumps for noble gases. One of these attempts is disclosed in U.S. Pat. No. 3,198,422 to Kienel which describes a "diode" type sputter-ion pump which utilizes two separate pairs of cathodes constructed of at least two different metals, one of which is titanium and the other of which is selected from a group of relatively nonreactive metals such as silver, copper or gold. Accordingly, this pump describes a cathode structure comprised of a relatively reactive metal cathode and a relatively nonreactive metal cathode, the nonreactive cathode having a high sputtering yield and the reactive cathode having a low sputtering yield. As the result of such a configuration, the nonreactive metal is sputtered at high rates over the other portions of the cathode such as the titanium, and, of course, over the anode to thereby prevent the reevolution of the previously buried ions. One unfortunate limitation of the described pump is that during the sputtering operation the titanium portion of the cathode has its surface covered over with a relatively inert metal which causes a considerable decrease in the pumping capability for the active gases such as nitrogen, oxygen, water vapor and the like. In addition to the impaired ability of the pump to handle very low pressures, the pump also is very difficult to start.

Another prior art pump which is markedly improved over the Kienel pump is described in U.S. Pat. No. 3,398,879 and in an article entitled "Inert Gas Pumping Using Differential Sputter Yield Cathode", by Tom and James, Trans. 13th A.V.S. Symposium 1966. The pump described in this reference is also of the "diode" type configuration and utilizes a flat solid titanium cathode. Even though this pump has an increased ability to handle noble gases, when compared to the standard diode pump, this is believed to be due to the fact that tantalum sputters more readily than titanium. However, its ability to handle reactive gases is appreciably less.

Yet another two-metal cathode sputter-ion pump is described in an article entitled "Use of Molybdenum In Getter Ion Pumps" by Jackson and Haas, Inc., J. VAC. SCI. TECH. 3, 80, 1966. In this pump, a flat solid molybdenum cathode faces an identically shaped solid flat titanium cathode in "diode" type configuration. This combination of opposed reactive metals is capable of extreme vacuums, in excess of 10^{-10} Torr, but its pumping speed is low, particularly after an appreciable volume of gas is introduced into the pump which increases the pressure to above 10^{-5} Torr.

OBJECTS OF THE INVENTION

It is therefore a primary object of the present invention to provide an apparatus and a method for increasing the pumping capability of a sputter-ion pump for reactive gases.

It is a further object of the present invention to improve the starting characteristics of sputter-ion pumps.

It is still a further object of the present invention to provide a sputter-ion pump which pumps reactive gases more rapidly than was heretofore possible, particularly in the pressure range from 0.2 to 10^{-7} Torr, and which has an improved starting characteristic particularly after the introduction of a volume of gas into the previously highly evacuated pump.

It is still a further object of the present invention to utilize a new type of gettering material, and, more particularly, to form a getter alloy which comprises, as one of its components, no more than 90 percent and no less than 10 percent transition metal such as titanium and in which the remaining phases are highly reactive metals or metal alloys.

It is also an object of the present invention to provide a new and improved type of cathode structure for sputtering ions which gives better performance than with pumps known heretofore.

SUMMARY OF THE INVENTION

In accordance with a preferred embodiment of the present invention the cathodes, in an otherwise conventional type of sputter-ion pump, are made to sputter a gettering substance which is composed of at least two reactive metals, one of which is a transition metal such as titanium. Each cathode is constructed of at least two different reactive metals which are preferably arranged by alternating one reactive metal with another reactive metal in grid fashion to form the cathode. The two reactive metals may be arranged whereby one metal forms the columns and the other metal forms the rows of a grid structure or, in the alternative, columns of one metal alternating with columns of the other metal. In the preferred embodiment of the present invention the cathodes are "transparent" to form what is generally known as a "tritide" pump.

25 The present invention is also disclosed in a paper by Dr. Lewis D. Hall published in Transactions of the 15th A.V.S. Symposium, Oct. 30, 1968, and the disclosure made in this paper is expressly included by reference into this specification.

BRIEF DESCRIPTION OF THE DRAWINGS

FIG. 1 diagrammatically illustrates a sputtering system having a pump with a pair of cathodes constructed in accordance with the present invention;

FIG. 2 is an end view of a cathode constructed in accordance with the present invention;

35 FIGS. 3-6 illustrate, diagrammatically, a number of embodiments of the cathode structure of the present invention; and

and FIG. 7 is a graph showing the vacuum achieved as a function of pumping time, *i.e.*, pumping speeds, for triode type pumps having conventional cathodes and cathodes constructed in accordance with the present invention.

DESCRIPTION OF THE PREFERRED EMBODIMENTS

Referring now to FIG. 1 of the drawing, there is shown in schematic block diagram form a sputter-ion pumping system of the type well known in the prior art but having a novel cathode structure in accordance with the present invention. The system illustrated includes an evacuable chamber 10, of which it is desired that the pressure be reduced to 1×10^{-5} Torr or below. A mechanical pumping means 12 is typically provided in the system for pumping the chamber down to approximately 10^{-3} Torr, at which time the valve means 14 is closed and the sputter-ion pump is actuated to further reduce the pressure in the chamber 10 to a vacuum well in excess of 10^{-3} Torr.

10 1911. The sputter-ion pump is essentially comprised of a vacuum enclosure 16 of nonmagnetic metal positioned between a pair of magnetic poles 18 and 20 for establishing a magnetic field across the pumping chamber 22. Disposed within the pumping chamber 22 is an anode structure so as to provide an improved electrostatic field, and two "transparent" cathode structures 26 and 28 from which the sputtering action is generated. Transparent, as used herein, is defined as having at least one aperture therein such that the sputtered material can pass through the cathode.

Whereas in the prior art structures, the cathode plates were usually constructed from one of a number of reactive metal substances, the novel structure in accordance with the present invention employs two or more reactive metals in order to produce an "alloy vapor" and cause the formation of alloy deposits over as much of the internal pump area as possible. In this way, a considerable improvement over the results obtainable with the single substance cathodes perhaps the best of which is titanium is obtained.

In the illustrated structure the anode 24 is electrically connected to the walls of the enclosure 16 defining the chamber 22, and the two are maintained at ground potential. The cathodes 26 and 28 are charged to a high negative potential with respect to ground. The cathode structure, as illustrated in the several embodiments shown in FIGS. 2 through 6, is comprised of various arrays of two or more different reactive metals in strip form. The cathodes may be comprised of any suitable configuration of metallic strips which may be positioned in gridlike form or louver form, or in any other suitable configuration.

The principal feature of the present invention is that the strips comprising the array are constructed of at least two different types of reactive metal and are arranged in a predetermined manner, so as to provide a mixing of the vaporized materials, either before or after they have condensed upon the surfaces of the pumping chamber.

Thin vapor alloy producing techniques have been found to produce pumping characteristics which greatly exceed those of the prior art. In operation, a high negative potential is applied to the cathodes 26 and 28 via a conductive lead 30, which passes through a conducting block 32, positioned in the wall of the enclosure housing 16. Since the housing 16 and the anode 24 are grounded, and thus operate at zero potential, the effect of applying the high negative potential to cathodes 26 and 28 is to produce a region of intense electric field between the anode 24 and the cathode plates 26 and 28. Within the region between the anode 24 and the cathode plates 26 and 28 a stray electron will be attracted towards the positive anode 24. As it travels toward anode 24, the electron will gain kinetic energy and may collide with a neutral gas molecule within the chamber 22.

Assuming the electron has gained sufficient energy, it will ionize the neutral molecule and produce a free electron and a positive ion. The positive ion will then be attracted to the cathode plate because of its high negative charge. Upon striking the gridlike elements of the cathode the ion will disintegrate portions thereof, and also cause secondary electrons and protons to be emitted which may further enhance the ionization of the gas within the chamber 22. The vaporized particles of the cathode materials which are dislodged by the ion bombardment form a vapor within the interior of the chamber 22 which is then caused to condense upon the interior surfaces thereof. Since the cathode materials are of a reactive metal, the sputtered material serves to entrap other gaseous molecules that it happens to come in contact with.

By utilizing two or more different metals in the cathode structure, physically positioned closely proximate one another, a pumping action is achieved which greatly exceeds the pumping rate of prior art structure. This is believed to be a result of a mixing of the vapors of the two different reactive materials, so as to, in effect, provide an "alloy vapor" which is substantially the same as would be obtained from sputtering an alloy of the separate materials. The cathode plates may be made of a combination of any of the metallic substances such as molybdenum, chromium, tungsten, tantalum, niobium, iron, titanium, zirconium, nickel, barium, aluminum, thorium, magnesium, vanadium, hafnium, or other transition elements of the fourth, fifth or sixth groups of the periodic table including the rare earths, as well as the semiconductors boron, silicon and germanium. Silicon is of particular interest because of its known tendency to form oxides and nitrides.

One of the principal requirements of a good sputter-ion pumping means is that it have high gas handling capability. That is, it must be able to pump rapidly down to a high vacuum gain after an appreciable volume of gas is introduced into the system which is being maintained at a high vacuum. In accordance with the present invention, a considerable improvement over the results obtainable with single-metal titanium cathodes is obtained.

In order to illustrate the improved characteristics of the novel cathode structure of the present invention and, in particular, the increased pumping rate, reference is made to FIG.

7 of the drawing which is a graphical comparison between a slatted grid structure of titanium only and a physically similar slatted structure wherein the alternate titanium slats were replaced with zirconium slats. The cathodes consist of rows of thin metal slats of approximately .025 inches $\times$ $\frac{1}{8}$ inches $\times$ 2- $\frac{1}{2}$ inches, and are spaced about one-eighth inch center to center. The titanium structure was chosen as a reference since it is universally used in commercial "triode" pumps, and in most commercial "diode" pumps. Furthermore, the literature to date indicates that for pumps in which a single metal cathode is used no metal has given better results than titanium, although in some of the tests, zirconium alone was used and was found to give essentially identical results to titanium.

The tests, exemplary results of which are illustrated in FIG. 7 of the drawing, were made by connecting two sputter-ion pumps in parallel in a system such as is illustrated in FIG. 1. With the system initially pumped down to about 4×10^{-6} Torr, all pumps were turned off. The pressure was then allowed to rise and at 1×10^{-3} Torr the B-A gauge was turned off, since this is its upper limit. After a specified period of time the pump under test was turned on and the values of the pressure v. time were recorded. This procedure was followed repeatedly for the all-titanium cathode and the experimental cathode in turn. The results were found to be quite reproducible. It is estimated that the maximum pressure at the start of each pump-down was about 30 microns when 40 minutes were allowed to elapse after turning off the B-A gauge.

In FIG. 7, the solid lines represent the results obtained using the all-titanium cathode on one hand, and the titanium-zirconium cathode on the other hand, each being turned on 20 minutes after the B-A gauge was turned off. The dashed lines represent corresponding tests initiated 42 minutes after the B-A gauge was turned off. These curves dramatically illustrate the outstanding superiority of the novel cathode structure using alternate slats of titanium and zirconium over the prior art structure using titanium alone.

In FIGS. 2 through 5, various alternative configurations of dual material cathode structures are illustrated. The slats designated A are of one type of material, such as titanium, for example, and slats designated B are of another type of material, such as zirconium or vanadium, for example. To summarize, material A may be of any element from atomic number 21 (Sc) through 28 (Ni); 39 (Y) through 42 (Mo); 57 through 74; or 89 (Ac) through 92 (U). Material B (C, D, etc.) may be from the same set as A, but further including Be, Mg, Ca, Sr, Ba, B, Al, C, Si or Ge.

In FIG. 6 a trimetal cathode structure is illustrated which includes a first metal A, such as titanium, a second metal B, such as zirconium, and a few strips of a third metal C, such as aluminum, which were arranged across the titanium and zirconium strips A and B. This structure was found to give one of the fastest pump-downs obtained during the initial tests of the novel cathode structure.

It is, of course, to be understood that the illustrated configurations of the dual-metal and trimetal cathode structures are merely illustrative in nature, and are not to be construed as limiting the forms of cathode structure contemplated for use in carrying out the invention. As an example, the cathode structure may be comprised of an interwoven mesh of two or more different types of metals, or may consist of a honeycombed like structure comprised of a plurality of cylindrical segments of different types of metal. Moreover, the structure may take any other suitable form in which the two or more different types of metals are positioned proximate one another, so that the vapors created by the sputtering action will become intermixed during their flight to condense on an interior surface of the structure. Furthermore, it is contemplated that in the case of the "diode" type pumps, two or more metals might be laminated together to form a striplike surface wherein alternate stripes are of one type of metal and the remaining stripes are of another type of metal.

After having read the above disclosure, many more alterations and modifications of the invention will be apparent to

those of skill in the art. It is to be understood that this description of preferred embodiments is for purposes of illustration only and is in no manner intended to be limiting in any way. Accordingly, I intend that the appended claims be interpreted as covering all modifications which fall within the true spirit and scope of my invention.

I claim:

1. In a sputter-ion pump apparatus using the principle of cathode disintegration by ion bombardment and including a vacuum envelope enclosing a evacuable volume, an anode structure, a pair of substantially identical cathodes for disintegration by ion bombardment and, means for establishing substantially identical electric fields between said anode structure and each of said cathodes, the improvement comprising: cathodes comprised of at least two different types of reactive gettering materials distributed in a substantially uniform manner so as to form the operative surface of said cathodes.

2. In a sputter-ion pump apparatus as recited in claim 1 wherein said cathodes are formed of a plurality of members in which groups of members of one type of reactive gettering material are alternatively positioned with respect to groups of another type of reactive gettering material.

3. In a sputter-ion pump apparatus as recited in claim 2 wherein one of said reactive gettering materials consists of titanium and the remaining gettering materials are selected from the group consisting of zirconium, cobalt, tungsten, hafnium, iron, niobium, tantalum, molybdenum, silicon, boron and germanium.

4. A sputter-ion pump apparatus as recited in claim 2 wherein one of said reactive gettering materials consists of zirconium and the remaining gettering materials are selected from the group consisting of titanium, cobalt, tungsten, hafnium, iron, niobium, tantalum, molybdenum, silicon, boron, and germanium.

5. A sputter-ion pump apparatus as recited in claim 2 wherein one of said reactive gettering materials consists of aluminum and the remaining gettering materials are selected from the group consisting of titanium, zirconium, cobalt, tungsten, hafnium, iron, niobium, tantalum, molybdenum, silicon, boron and germanium.

6. In a sputter-ion pump apparatus as recited in claim 2 wherein said members are spacially separated so as to render said cathodes transparent.

7. In a sputter-ion pump apparatus as recited in claim 1 wherein a selected portion of each cathode is of one reactive gettering material and remaining portion of the cathode is of another reactive gettering material.

8. In a sputter-ion pump apparatus as recited in claim 1 in which the operative surface of each cathode is formed of at least two different reactive gettering materials which are interspersed with one another.

9. In a sputter-ion pump apparatus as recited in claim 8

wherein portions of one type of reactive gettering material alternate with portions of another type of reactive gettering material.

10. In a sputter-ion pump apparatus as recited in claim 9 wherein said portions are spaced apart closely proximate to one another.

11. In a sputter-ion pump apparatus as recited in claim 1 wherein each cathode is formed of one or more alloys of the reactive gettering materials.

12. A method of producing an alloy of two or more materials by sputtering, comprising the steps of:

providing an anode structure within an evacuable housing; providing a cathode structure within said housing having an operative portion which is constituted of a plurality of discrete members of which at least one of said members is selected from the group consisting of titanium, aluminum and magnesium, and the balance of said members is of at least one other reactive material selected from the group consisting of zirconium, tungsten, hafnium, niobium, tantalum, molybdenum, chromium, iron, cobalt, silicon, boron and germanium; producing an electric field between said anode structure and said cathode structure; establishing a magnetic field substantially parallel to said electric field; and evacuating said housing.

13. A method of producing an alloy of two or more materials as recited in claim 12 which further includes the step of spacing said one members from said other members so that the vapors produced by particle collision with the respective cathode members are caused to intermix prior to condensing upon a surface within said housing.

14. A sputter-ion pump comprising:
an evacuable enclosure;
an anode structure disposed within said evacuable enclosure;
a pair of substantially identical cathodes within said enclosure comprised of a plurality of members of at least two different reactive getter materials;
potential supply means connected between said anode structure and said cathodes for rendering said cathodes more negative than said anode structure; and
a pair of pole pieces for establishing a magnetic field within said evacuable enclosure.

15. A sputter-ion pump as recited in claim 14 wherein said members are elongated and disposed closely proximate one another in spaced apart relationship.

16. A sputter-ion pump as recited in claim 15 wherein alternate ones of said members are of one type of reactive gettering material and the remaining members are of another type of reactive gettering material.
